UNITED STATES PATENT OFFICE.

WILLIAM C. HANNA, JR., OF NEW YORK, N. Y.

DESIGN FOR A RAILING.

SPECIFICATION forming part of Design No. 21,980, dated November 8, 1892.

Application filed October 15, 1892. Serial No. 449,152. Term of patent 7 years.

To all whom it may concern:

Be it known that I, W. C. HANNA, Jr., a citizen of the United States, residing at New York, (Kingsbridge,) in the county of New

5 York and State of New York, have invented a certain new and original Design for a Railing, of which the following is a specification.

10 My invention relates to a new design for railings, and is illustrated in the accompanying drawing, which is a side elevation.

15 A indicates the main hand-rail, and BB the upright posts, which divide the railing into separate panels. In each of the panels is a bar C, extending off at right angles to the posts, the rear end of each bar being curved to form a scroll D.

20 E indicates an inclined or diagonal bar substantially parallel with the rail A, the said bar being twisted at a point between its ends, as shown. Beneath the bar C is a scroll or

bracket F, which is shown as united to the scroll or bracket D and bar C by a band a. A scroll or bracket G connects the bars E with the posts.

At the upper end of the railing there are 25 two bars C, between which are arranged two scrolls and the inclined bar E. The rear end of each of the bars C is extended upward in curved or wavy form. At the base or lower end of the railing there is a bracket H. 30

I claim—

The design for a railing herein shown and described.

In witness whereof I hereunto set my hand in the presence of two witnesses.

W. C. HANNA, JR.
